FUR STRETCHER

Charles Herbert Olds, Prince George,
British Columbia, Canada

Application December 22, 1948, Serial No. 66,601

3 Claims. (Cl. 45—24)

1

This invention relates to fur stretchers and more particularly to a type of stretcher adapted to be used for the purpose of curing and drying skins and pelts of newly killed animals.

The invention broadly consists of a single length of resilient material bent medially thereof and both arms extending angularly therefrom in a common plane.

At a point near the extremity of said arms are pivotally secured a pair of lock bars held together by means of a thumb nut.

The primary object of the invention is to provide means for separating the arms after a fresh pelt has been stretched thereon.

A further object is to provide locking means on said stretching means.

Another important object is to provide hooks at the extremity of each locking arm to secure the pelt thereon and prevent same from slipping during the drying and curing period.

In devices of this character as hereinbefore used, a taut skin had a tendency to creep up on the arms and since the arms were generally formed with a plurality of teeth, the skin was very often torn and became worthless.

It is therefore a further object of the invention to provide a hook on each side of the fur stretcher to prevent a taut skin from creeping up.

Another still important object of the invention is to provide a thumb screw on the transversal members which will permit the device to be adjustable to various widths.

With these and other objects in view that may appear while the description proceeds the invention consists in the novel arrangement of cooperating elements as hereinafter more specifically set forth, claimed and shown in the accompanying drawing forming part of this application and in which:

Fig. 1, is a side elevational view of the invention;

Fig. 2, is a detail of one of the cross arms and

Fig. 3, is a view in direction of the arrow in Fig. 2.

Referring more in detail to the drawing in which similar reference characters designate corresponding parts throughout the several views it will be seen the invention consists of a single length of flexible resilient material bent medially at 10 and having a substantially large radius. The arms 11 extend angularly away from the rounded extremity 10. At a point near the extremity of the arms a flat portion 12 is formed for the purpose of pivotally securing the cross arms 13 and 14. The said cross arms are secured to the flat portions 12 by means of rivets or the like and extend beyond the limit of the arms 11. At each free extremity of cross arms 13 and 14 is formed a hook 15 with a downwardly projecting point.

The skin is pushed over the stretcher and is held thereon by means of the points 15.

2

Since the skins vary in width it is essential that the stretcher be adjustable in that direction. This feature is provided by means of the arms 13 and 14. The said arms are pivoted at 16 and are joined centrally of the stretcher by means of a thumb screw 17. By raising the centre point 17 until it is in the same plane as pivot points 16 the device will gain in width. To prevent a taut skin from closing in the arms 11, the cross arm 13 is formed at right angles at 18 and its extremity projects upwardly at 19 so that the upright portion comes in contact with cross arm 14 and prevents further movement thereof.

To remove the skin from the stretcher the cross arms 13 and 14 are released and the center point brought downwardly until the points 15 are free from the skin. The dried skin may then easily be removed.

It is believed that the construction and advantages of the invention may be apparent from the foregoing paragraphs taken in conjunction with the accompanying drawings without further detailed description.

While the preferred embodiment of the invention has been disclosed it is understood that minor changes in the details of construction, combination and arrangement of cooperating parts may be resorted to within the scope of what is claimed without departing from the spirit of the invention.

I claim:

1. A fur stretcher comprising a frame made of a single length of flexible resilient material, a pair of arms extending angularly therefrom, a flattened portion formed near the free extremity of said arms, a pair of cross arms pivotally secured to said portion, a hook formed on the free extremity of each cross arms, means to secure said cross arms in a predetermined position, and means to prevent the stretcher from folding beyond a predetermined position.

2. In a stretcher as claimed in claim 1, said first mentioned means consisting of a thumb screw to adjustably secure said cross arms in a predetermined position.

3. In a stretcher as claimed in claim 1, said last mentioned means consisting in the extremity of one of said arms formed at right angle thereto to abut against the cooperating arm.

CHARLES HERBERT OLDS.
